UNITED STATES PATENT OFFICE.

JAMES B. MUNDELL, OF CHICAGO, ILLINOIS.

INNER TUBE.

Application filed March 28, 1921. Serial No. 456,348.

To all whom it may concern:

Be it known that I, JAMES B. MUNDELL, a citizen of the United States, and a resident of the city of Chicago, in the county 5 of Cook and State of Illinois, have invented certain new and useful Improvements in an Inner Tube; and I do hereby declare that the following is a full, clear, and exact description of the same, reference being had 10 to the accompanying drawings, and to the numerals of reference marked thereon, which form a part of this specification.

This invention relates more particularly to an improved type of an inner tube for 15 tire casings, said tube being divided by partitions radiating from the inner periphery and dividing the interior of the tube into independent endless chambers all of which are adapted to be simultaneously inflated by 20 a single valve mechanism.

It is an object of this invention to divide an inner tube into a plurality of independent chambers radiating from the inner periphery of the interior of the tube.

25 A further object of the invention is the construction of an inner tube divided into endless valve controlled compartments all of which communicate with a common chamber having an air valve connected therewith.

30 It is an important object of this invention to provide an inner tube of simple and effective construction wherein a plurality of compartments communicate with a common valve through a chamber afforded by a cap vulcanized to the inner peripheral surface 35 of the inner tube to separate said valve from said compartments.

Other and further important objects of 40 this invention will be apparent from the disclosures in the specification and drawings.

The invention (in a preferred form) is illustrated in the drawings and hereinafter more fully described.

45 On the drawings:

Figure 1 is a perspective view of an inner tube embodying the principles of this invention, with a portion broken away to illustrate the interior construction.

50 Figure 2 is an enlarged fragmentary detail section taken on line 2-2 of Figure 1 showing the valve mechanism.

Figure 3 is an enlarged detail section on line 3-3 of Figure 2 with the tube disposed 55 within a tire casing.

Figure 4 is an enlarged fragmentary detail section of the valve mechanisms for inflating the various tube chambers.

As shown on the drawings:

The reference character 1 indicates a tire 60 casing having disposed therein an improved inner tube of this invention. The inner tube comprises an endless rubber tube 2, to which is attached in the regular manner an air supply valve 3. Vulcanized or otherwise integrally secured on the interior of the tube 2 is a curved circular cap 4, which encloses the inner part of the valve 3 within the chamber 5 formed by said cap. The interior of the tube 2 is divided into a plurality of endless chambers or compartments 6 by means of a plurality of endless partitions or webs 7. The partitions 7 are arranged in fan shaped relation within the tube 2 radiating from the inner periphery 75 of the tube. The cap 4 is provided with a plurality of air inlet openings or ports 8, one for each of said compartments 6. Mounted within each compartment 6 upon the cap 4 is a flap valve 9 adapted to be 80 closed by the pressure of the air within the compartment to prevent escape of air therefrom.

When air is pumped through the valve 3 it passes through the tube opening 10 into 85 the common air supply chamber 5 formed between the inner surface of the tube 2 and the cap 4. The compressed air in the chamber 5 forces the flap valves 9 open, thereby permitting air from the chamber 5 to flow 90 through the air ports 8 into the various compartments 6 at the same time. As soon as the pressure of the air in the compartments 6 becomes greater than the pressure 95 of the air in the chamber 5 the flap valves 9 are closed.

It will be noted that the compartments 6 are independent of each other. Should any one of the compartments be punctured the tube 2 will still be fit for use, since the remaining compartments will expand sufficiently to take up the space of the punctured compartment.

The partitions 7 are of different widths, as illustrated in Figure 3, and divide the inner tube 2 into a plurality of continuous compartments of different volumes. The middle compartment is the largest while those on each side of the middle compartment are proportionately smaller.

I am aware that numerous details of construction may be varied through a wide range without departing from the principles of this invention, and I therefore do not 5 purpose limiting the patent granted otherwise than necessitated by the prior art.

I claim as my invention:

The combination with an inner tube of 10 integral partitions radiating from the inner periphery of the tube and dividing the tube into different sized compartments, an air valve connected to said tube, an integral cap over said valve on the inside of the tube

provided with individual air ports communicating with each compartment, and individual flaps over each of said air ports on the inside of the compartments to prevent release of air into said cap. 15

In testimony whereof I have hereunto subscribed my name in the presence of two 20 subscribing witnesses.

JAMES B. MUNDELL.
